[57] CLAIM

The ornamental design for a practice model for a tracheostomy, as shown.

DESCRIPTION

FIG. 1 is a perspective view of a practice model for a tracheostomy, showing my new design;

FIG. 2 is a side elevational view thereof, the opposite side elevational view being identical thereto;

FIG. 3 is a front elevational view thereof, the rear elevational view being identical thereto; and,

FIG. 4 is an end elevational view thereof, the opposite end elevational view being identical thereto.

FIG. 1

FIG. 2

FIG. 3

FIG. 4
